UNITED STATES PATENT OFFICE.

AARON M. BILLSTEIN, OF RIDERWOOD, MARYLAND, ASSIGNOR TO THE LORD BALTIMORE PRESS, OF BALTIMORE, MARYLAND, A CORPORATION OF DELAWARE.

DISPLAY-BOX.

1,149,891.

Specification of Letters Patent. Patented Aug. 10, 1915.

Application filed May 16, 1914. Serial No. 839,013.

To all whom it may concern:

Be it known that I, AARON M. BILLSTEIN, a citizen of the United States, and resident of Riderwood, Baltimore county, State of Maryland, have invented certain new and useful Improvements in Display-Boxes, of which the following is a specification.

The present invention relates to improvements in knock down or folding display boxes and will be described in connection with the accompanying drawings, in which,

Figure 1 is a plan of the blank from which the embodiment of the invention selected for purposes of illustration is formed; Fig. 2 is a perspective view of the improved box with the cover arranged to display the contents; Fig. 3 is a sectional view on the line 3—3 of Fig. 2; Fig. 4 is a sectional view on the line 4—4 of Fig. 2; Fig. 5 is a view similar to Fig. 4 showing the top in a different position; Fig. 6 is a view illustrating the position of the several parts when arranged to provide a complete inclosure of the contents of the box; Fig. 7 is a sectional view through one of the ends of the box with the parts arranged as in Fig. 6; Figs. 8 and 9 illustrate a slight modification, the former being a section on the line 8—8 of Fig. 9.

Referring to the drawings it will be seen that the blank from which the box is formed comprises a bottom section A of rectangular form, a front side wall including two sections B, B', divided by a score b, a rear side C separated by a score c from the top, and end and cover members which will be more particularly described hereinafter.

The front and rear side sections B, C, are provided at both ends with similar extensions D, E, separated from the said side wall sections by suitable scores d, e, and in one edge of each of said extensions is formed a notch, d', e', whereby said end sections D, E, may be interlocked when the sides C, D, are turned into position at right angles to the bottom A and toward each other.

The bottom section A is separated by scores a from two extensions each comprising two sections F, F', separated by a score f. In assembling the box the end sections F, F', are bent along the score f and then turned about the scores a so as to extend over the upstanding end members D, E, after which the front side section B is turned up on the score line a' and the section B' is folded inwardly to complete the

body of the box. A tab F² is cut from each section F' so that tabs on the cover, as hereinafter more particularly described, may be introduced between the overlapping end members D, E, or between said members D, E and the section F.

The cover of the box comprises two main sections H, H', separated by a score h; similar end sections each including members I, I', separated by continuations of the score h, and separated from the body of the cover by scores i; and a front edge member H², the ends of which are divided from the body thereof by scores h² which are substantially in alinement with the scores i. A score h⁴ separates the front edge member H² and the cover section H'. Furthermore, each end section of the top or cover is provided with a tab or projection K separated from the ends by scores h'. The end sections of the cover are adapted to be folded on the lines of the scores i, i', to lie against either the inner or outer surface of the cover and the latter and the overlapping end sections can then be bent on the line of the score h to occupy the position shown in Figs. 2 and 4 or that shown in Fig. 5.

In folding the cover into the position shown in Fig. 2, the front edge member H² is turned inwardly so that it will extend horizontally, the ends H³ thereof being bent downwardly so that they pass through the apertures formed in the end sections F', by cutting the tabs F², and into the space between the end sections D, E, or between the latter and the end sections F. Notches h⁵ are preferably provided in the members H³ so that when the parts are positioned as just described said sections H³ will be locked to the adjacent end of the body of the box by reason of portions of the forward edges of the apertures formed by cutting the tabs F² entering said notches.

In folding the top into the position shown in Fig. 5, the section H' thereof is turned on the score line h in the opposite direction from that in which it was turned in assuming the form shown in Figs. 2 and 4; and the edge member H² lies against the outer surface of the rear side C, the ends H³ extending forward between the end sections E, F.

It will be seen that with the parts arranged as described and as illustrated in either Figs. 2 and 4 or 5, the cover or top

of the box is so positioned that it forms an upwardly extending display surface, corresponding in area to the section H' or H of the blank, which display surface is securely held at such an angle to the body of the box as to permit free inspection of the contents without having an unduly or undesirable high extension at the rear. That is, the upward extension on which, if desired, suitable advertising or display matter may be arranged, is of less height than the width of the box. This is of considerable importance in many instances as it enables the box to be arranged in front of other articles on a counter or shelf without concealing the articles in rear thereof. With the parts arranged as in Figs. 2 and 4 it will be seen that the front surface of the top section H which as described is intended to receive suitable advertising or display printing is the outer surface of the blank or the same surface thereof as forms the outer faces of the bottom, sides and end walls. This is of practical importance as the material from which such boxes are commonly made is as a rule provided with a better finish or surface on one face than on the other; and the arrangement particularly illustrated in the figures referred to enables all of the printing to be done at a single operation and provides for such printing being upon the better finished face or surface of the blank. However, the parts may be arranged as shown in Fig. 5 and by this arrangement the display surface is practically entirely in rear of the box so that no portion of the contents thereof is covered by the top.

When the parts are arranged, as shown in Fig. 2, the tabs F^2 will extend vertically so as not to project beyond the end walls of the box or in any way mar the neat appearance thereof. Said tabs are of practical utility as by means thereof a slight separation of the end members of the box may be effected to assist in inserting the cover tabs H^3 .

It is not necessary that the cover members H^3 extend through the openings formed in cutting the tabs F^2 . If desired the cover can be positioned substantially as shown in Fig. 2, the member H^2 being in rear of the tabs F^2 , which serve to hold the top in the desired bent form, and the members H^2 extending vertically against the inner faces of the ends of the box. Or again, as shown in Figs. 8 and 9, tongues L may be cut from the end sections F' and the cover members H^3 positioned between them and the inner surfaces of the sections F' to hold the top in the desired position.

The improved box may, if desired, be utilized as a shipping container, as shown in Figs. 6 and 7. When arranged for such use the member H^2 may be positioned over

the outer face of the side B with its ends H^3 extending over the ends of the box and held in position by the cover end sections I , I' , the tabs K extending beneath the bottom of the box to which they may be secured by paste or other suitable means. Or said member H^2 can be positioned to contact with the inner surface of the front section B' with the parts H^3 bearing against the inner faces of the ends of the box.

It will be seen that by the construction described the ends and the front wall of the box are of double thickness, the ends in fact having four thicknesses of material, so that a strong and substantial box may be produced from relatively light weight material. The blanks can be shipped in flat form and readily assembled or, as previously explained, the parts may be arranged to provide a completely closed package or container. Also it will be evident that as regards some of the features of the invention the form and manner of scoring the blank to produce the bottom, sides, and ends, as well as the manner of connecting these parts, may be varied from that illustrated.

Having described the invention what is claimed and desired to be secured by Letters-Patent is,

1. A box formed from a single blank, divided by suitable scores so that it is adapted to form a bottom, sides, ends and a top, the ends of the complete box each comprising inner sections, extending forwardly and rearwardly from the front and rear side walls respectively, and outer sections extending upwardly from the bottom over the upper edges of said inner sections, and downward over the inner faces of the latter, each of said outer sections having an aperture formed therethrough, and the top being divided, by longitudinal scores, into three sections H , H' , H^2 , adapted to extend continuously and completely over the area enclosed by the sides and ends of the box and one of said sections terminating in tabs adapted to extend downward through the apertures in the outer sections of the ends of the body when the top is bent about the score separating the other sections, whereby the latter will be held in position to constitute a display surface extending above the body of the box.

2. A box formed from a single blank divided by suitable scores so that it is adapted to form a bottom, sides, ends, and a top, the latter being scored to form end sections, adapted to be folded against the inner surface of the main section of the top or to project over the outer surfaces of the ends of the body, having a score h extending throughout its length, including both said end sections, whereby the top may be bent to provide an upwardly extending display surface over the rear por-

tion of the body, and having at its free edge a member H^2 adapted to extend horizontally from one end wall of the body to the other or in contact with the front wall of the body, said member terminating in tabs adapted to extend downwardly between sections of the end walls of the body when only the rear portion thereof is covered by the top or to contact with said end walls

10 when the body is fully covered by the top.

3. A box formed from a single blank divided by suitable scores so that it is adapted to form a bottom, sides, ends, and a top, the latter being scored to form end sections, 15 adapted to be folded against the inner surface of the main section of the top or to project over the outer surface of the ends of the body, each having a tab K at its outer edge, the top being additionally provided 20 with a score h that extends throughout the length of the top, including both the end sections, whereby the top may be bent to provide an upwardly extending display surface over the rear portion of the body, tabs 25 H^2 being provided at the ends of the top beyond the aforesaid end sections thereof and adapted to extend downwardly between sections of the end walls when the top is bent along the line of the score h , 30 for the purpose described.

4. A collapsible box comprising a bottom, sides, ends, and a top, the latter being provided with end sections adapted to be folded against the main section or to project 35 therefrom in contact with ends of the box and having a score h extending throughout its length including both said end sections whereby the top and the end sections thereof may be bent on said score h to provide 40 an upwardly extending display surface or be caused to cover the entire area of the box.

5. A collapsible box comprising a bottom, sides, ends, and a top, the latter having a

body portion adapted to cover the box, end 4 sections adapted to fold against either face of the body portion, and an edge section adapted to extend at an angle to or lie in substantially the same plane as the adjacent portion of the top, a score h extending 5 throughout the length of the top including said end sections, and the edge section of the top being adapted to engage the ends of the box when the top is bent on the line of said score h , for the purpose described. 5

6. A collapsible box comprising a bottom, sides, ends and a top, the latter having a body portion adapted to cover the box, end sections adapted to fold against either face of the body portion, and an edge section H^2 6 adapted to extend at an angle to or lie in substantially the same plane as the adjacent portion of the top, said edge section having foldable ends H^3 , a score h extending throughout the length of the top including 6 said end sections, whereby when the top is bent on the line of said score h the members H^3 may be engaged with the ends of the box to maintain the cover in an upright position. 7

7. A collapsible box comprising a bottom, sides, ends, and a top, the latter being provided with end sections adapted to be folded against the main section thereof or to project therefrom in contact with the ends and 7 bottom of the box, said top being foldable on a line extending throughout its length including said end sections, whereby it is adapted to cover the entire area of the box and extend across the ends thereof or to 80 provide an upwardly extending display surface.

In testimony whereof I affix my signature in presence of two witnesses.
